COMBINED BOBBY PIN AND PERFUME
HOLDER

Joan Weiss, New York, N. Y.

Application May 2, 1950, Serial No. 9,628

Term of patent 14 years

(Cl. D86—10)

To all whom it may concern:

Be it known that I, Joan Weiss, a citizen of the United States of America, residing in New York city, county of New York, and State of New York, have invented a new, original, and ornamental Design for a Combined Bobby Pin and Perfume Holder, of which the following is a specification, reference being had to the accompanying drawing, forming part thereof, wherein,

I claim:

The ornamental design for a combined bobby pin and perfume holder, substantially as shown.

JOAN WEISS.
